UNITED STATES PATENT OFFICE.

ROBERT ADOLPH, OF NEW YORK, N. Y.

WATCH-PROTECTOR.

SPECIFICATION forming part of Letters Patent No. 766,409, dated August 2, 1904.

Application filed April 26, 1904. Serial No. 204,949. (No model.)

To all whom it may concern:

Be it known that I, ROBERT ADOLPH, a citizen of Germany, residing at New York city, Brooklyn, county of Kings, and State of New York, have invented new and useful Improvements in Watch-Protectors, of which the following is a specification.

This invention relates to a watch-protector adapted to be secured within the watch-pocket of a garment and so constructed as to effectively prevent the unauthorized abstraction of the watch.

In the accompanying drawings, Figure 1 is a section through part of a garment provided with my improved watch-protector; Fig. 2, a front view of the protector, showing the jaws closed and locked; Fig. 3, a similar view with the disk removed and showing the jaws closed and unlocked; Fig. 4, a similar view showing the jaws open; Fig. 5, an end elevation, partly in section, of the protector; Fig. 6, a detail showing the jaw-locking lugs and keeper, and Fig. 7 an inner view of the disk.

The letter *a* represents a flattened circular case made of rigid material and provided with an upper peripheral slot or mouth *a'*, adapted for the introduction of the watch *A*. To the bottom of case *a* is secured a bar *b*, adapted to be attached to the vest or other garment *B* within the watch-pocket by threaded pins *b'* and nuts *b''*. From the bar *b* depends a tab *c*, having buttonhole *c'*, by which it may be secured to the trousers *D*. Thus the case *a* is locked to the garment, and any pull on the same will be readily felt.

The mouth *a'* of case *a* is adapted to be opened or closed by means of a pair of jaws *d* and *e*, which straddle the case and are so connected as to simultaneously open or close. The first jaw, *d*, is operated by the fingers, for which purpose it is milled, as at *d'*, and transmits its motion, but in a reverse direction, to second jaw, *e*. For this purpose the jaw *d* is provided with an arm *d''*, attached to the inner side of a disk *f*, rotatable upon a pivot *d'''* of case *a*. The disk *f* is preferably attached to case *a* by a slotted plate *g*, Fig. 2, which straddles pivot *d'''* and is screwed to the disk at *g'*.

From the inner side of disk *f* projects a pin *f''*, that engages a slot *h'*, formed in the inner arm of a two-armed lever *h*, pivoted to case *a* beneath disk *f*, as at *h''*. The lever *h* is contained within the opening *e'* of a slotted arm *e''*, with which the jaw *e* is provided and which extends between case *a* and disk *f*. It will be seen that by the means described the movement of jaw *d* will be transmitted, but in a reverse direction, by disk *f*, lever *h*, and arm *e''* to jaw *e*, so that the jaws are simultaneously opened or closed.

In order to securely lock the jaws in their closed position, the disk *f* is provided with a peripheral notch *f''* and with a notched plate *i*, secured to its inner side. The plate *i* is adapted to be engaged by a pawl *j*, pivoted to case *a* at *j'* and influenced by a spring *j''*. A pin *j'''*, projecting outwardly from pawl *j*, is adapted to engage a peripheral notch *f''* of disk *f*. The pawl *j* is operated by a button *k*, the shank *k'* of which is pivoted to the pawl *j* at *k''*. A keeper *l* embraces the shank *k'* and has a nose *l'*, which limits the play of pawl *j*.

It will be seen that by manipulating the button *k* the pawl *j* will release the plate *i*, and the pin *j'''* will simultaneously be withdrawn from notch *f''*, so that the jaws are released and may be opened. At their side the jaws *d* *e* are provided with lugs *d''* *e''*, respectively, Fig. 6, which are adapted to engage a keeper *m*, secured to the top of case *a*. Thus when the jaws are closed their lateral displacement is prevented.

The protector is permanently secured within the vest, and to open the same the button *k* is depressed, Fig. 3, and then the jaw *d* is drawn down to take the jaw *e* with it, Fig. 4. To close the case, the jaw *d* is drawn up to simultaneously raise jaw *e*, Fig. 2.

What I claim is—

1. A watch-protector comprising a slotted case, a pair of pivoted jaws, a rotatable disk secured to one of said jaws, and a lever engaged by the disk and adapted to engage the second jaw, substantially as specified.

2. A watch-protector comprising a slotted case, a pair of pivoted jaws, a rotatable disk

secured to one of said jaws, a pin on the disk, a lever having a slot which is engaged by the pin, and a slotted arm on the second jaw that is engaged by the lever, substantially as specified.

3. A watch-protector comprising a slotted case, a pair of pivoted jaws, means for simultaneously opening and closing the jaws, a bar secured to the bottom of the case, and a tab

depending from the bar, substantially as specified.

Signed by me at New York city, (Manhattan,) New York, this 25th day of April, 1904.

ROBERT ADOLPH.
